UNITED STATES PATENT OFFICE.

JOHN H. HINKEN AND JOHN E. TURNER, OF LOUISVILLE, KENTUCKY, ASSIGNEES TO THE TURNER DRIER COMPANY, OF CHICAGO, ILLINOIS.

DESIGN FOR A FILTER-PRESS PLATE.

SPECIFICATION forming part of Design No. 31,890, dated November 28, 1899.

Application filed October 26, 1899. Serial No. 734,891. Term of patent 14 years.

To all whom it may concern:

Be it known that we, JOHN H. HINKEN, a citizen of the United States, and JOHN E. TURNER, a subject of the Queen of Great Britain, residing at Louisville, county of Jefferson, and State of Kentucky, have invented and produced a new, original, and useful Design for Filter-Press Plates, of which the following is a specification, reference being had to the accompanying drawings, forming a part thereof.

Figure 1 is a front elevation of a filter-press plate of our design. Fig. 2 is a section on the line 2 2 on Fig. 1. Fig. 3 is a section on the line 3 3 on Fig. 1.

The characteristic features of this design consist in the form and relative arrangement of the superficial filter and drainage grooves and their disposition with respect to the induction and discharge apertures. Said grooves are—

First. The parallel vertical grooves 1 1, &c., which are closely arranged, occupying a circular area. A portion of these vertical grooves are interrupted by the annular un-grooved area 4, which surrounds the induction-aperture 5.

Second. Grooves 2 2 and 3 3, which cross the grooves 1 1, &c., the grooves 2 2 commencing near the upper side of the circular area occupied by the vertical grooves and di-

verging to right and left at angles approximating forty-five degrees to the vertical grooves, and the grooves 3 3 commencing near the circumference of said circular area at opposite sides of the center and converging toward a middle point near the circumference at the lower side of said area.

Third. A transverse groove 6, which crosses a portion of the vertical grooves 1 above the annular area 4, extending past said annular area a short distance at both sides.

Fourth. A groove 7, following the lower half of the circumference of said circular grooved area and subtending or crossing the lower ends of all the vertical grooves 1, as well as the mouth of the discharge-port 8.

We claim—

The design for a filter-press plate herein shown and described.

In testimony whereof we have hereunto set our hands, at Louisville, Kentucky, this 20th day of October, 1899.

JOHN H. HINKEN.
JOHN E. TURNER.
